UNITED STATES PATENT OFFICE.

FRANK P. BARNEY, OF CHARTLEY, MASSACHUSETTS.

BUTTON AND STUD.

1,120,786.

Specification of Letters Patent. Patented Dec. 15, 1914.

Application filed September 15, 1913. Serial No. 789,756.

To all whom it may concern:

Be it known that I, FRANK P. BARNEY, a citizen of the United States, residing at Chartley, in the county of Bristol and State of Massachusetts, have invented certain new and useful Improvements in Buttons and Studs, of which the following is a specification.

My invention relates to improvements in cuff-link buttons and studs, and it consists in the novel construction and arrangement of parts as hereinafter set forth and claimed.

My present improvement resides more especially in the type of cuff-buttons or studs in which the front head member of the button is rigidly secured to the adjacent end portion of the post. In the construction of buttons of this general class, as heretofore devised, the post is soft-soldered direct to the back of the button head; in others the head part is provided with a base-plate through which lugs formed on the post extend, and are riveted. In such former constructions having the post thus connected to the button head, the fastening means employed are liable to break or become weakened in that the post, when subjected to normal lateral stress or pressure acts as a lever, the tendency being to loosen it in or from the plate.

In the accompanying sheet of drawings, Figure 1 represents a side elevation of a button embodying my present improvement; Fig. 2 is a longitudinal sectional view, taken substantially through the center of the button; Fig. 3 is an outer end view of the front head; Fig. 4 is a transverse section taken on line 4—4 of Fig. 2, showing the pilot or "bean" head of the button; Fig. 5 is a face view of the post itself; Fig. 6 is an end view of the post combined with the back plate of the front head, the shoe member being omitted; and Fig. 7 is an edge view of the post, corresponding with Fig. 6.

a, in the drawings, designates the improved post-member of a button, the post being formed or cut from comparatively thick sheet metal stock. In the button represented the shank portion of the post is curved longitudinally, thereby adapting it for use in connection with cuff-link buttons, so-called. Obviously, the post is equally well adapted to be secured to the heads of studs. The main end portion is made comparatively wide and provided with parallel shoulders *a*¹, *a*¹, terminating in lateral ex-

tensions *a*², *a*², having oppositely bent right and left transverse ends or lugs *a*³, *a*³, substantially as shown. The smaller end of the post is passed through an elongated central opening *b*¹ formed in a thin, disk-like metal back-plate *b*, said opening being constructed to snugly receive the body portion of the post and engage its shoulders *a*¹ and having the face of the disk at the same time adapted to support the corresponding faces of the extensions *a*² and lugs *a*³. The plate may be recessed, as indicated at *b*², thereby increasing its stiffness and providing additional depth for supporting that part of the post. The head part of the button is provided with the usual cup-shaped sheet-metal outer shoe *c*. In applying the shoe, it is suitably positioned and held to receive the assembled back-plate and corresponding end of the post, followed by rolling the peripheral edge of the shoe to snugly engage the underside of the plate, thereby, too, causing the inner surface of the shoe to bear against the flattened lugs *a*³. As thus constructed, the post is rigidly secured against movement both in endwise and lateral directions. It will be noted that the said members of the post present a relatively large area to the plate *b*, and that the rolled shoe *c* rigidly clamps or presses the plate *b* and post *a* together and prevents any yielding of the members, whatever. The opposite or pilot end of the cuff-link button, frequently termed the "bean" end, is represented as having the post *a* provided with diametrically opposite shoulders *e*, *e*, a curved end part *e*¹ having small rounded extensions *e*², *e*² terminating in said shoulders *e*, *e*, and a short central lug *e*³, as clearly shown in Fig. 5; all said members being disposed in a plane common to the other portions of the post. An oval concavo-convex back-plate *h* of thin sheet stock is provided with a transverse opening *h*¹ in which the post is fitted (see Fig. 4). The outer rim of the plate *h* is adapted to receive and inclose the corresponding rim portion of the oppositely positioned metal lining plate *i*, the latter corresponding to the curved end part *e*¹ and having an opening *i*¹ to receive the said lug *e*³ of the post. The outer member of the "bean" consists of a concavo-convex shaped metal shoe *m* conforming to and engaging the said plate *i*; the several members of the smaller or "bean" end of the button are held together

against separation by slightly bending the peripheral edge portion of the shoe inwardly at an angle against the corresponding rim portion of the plate *h*, substantially as shown in Fig. 2. As thus constructed, the "bean" end is inexpensive to manufacture and presents a smooth, solderless, finished oval surface throughout, thereby adapting it to be easily inserted in the buttonhole and at the same time presenting an attractive appearance.

It will be observed that the improved construction of the front head is such that the post and back-plate *b* are capable of being readily assembled in an unsoldered state and positioned and held in the shoe *c* by a suitable tool or holder while the rim or flange portion of the shoe is being rolled inwardly; said rolling operation causing the shoe to forcibly engage the lugs or ears of the post superimposed upon the inner face of the plate *b*, said operation at the same time causing the rolled edge of the shoe to snugly engage the outer face of the plate, thereby rigidly securing the parts together without soldering, swaging or riveting.

I claim as my invention:

1. A button having oppositely disposed main front and back heads and a flat post uniting the heads, the said front head consisting of an outer shoe or cup having a circumscribing rim, an apertured, disk-like back plate fitting the inner periphery of said rim, the corresponding end portion of said post being comparatively wide and positioned in the apertured portion of the back plate; said post also extending laterally beyond the respective ends of said aperture and bearing on the said plate's proximate face, the inturned rim of the shoe clamping together the said parts of the front head against movement.

2. In a button or stud of the general

character described, the combination of a post, the head end of said post having oppositely arranged lateral extensions terminating respectively in bent right and left wings, a back-plate, and an outer shoe or cup member, the latter having the back plate and the corresponding head end of the post positioned therein, and having the edge of said shoe inturned, whereby the shoe engages both the back plate and the said lateral extensions of the post to maintain them rigidly in position in the head.

3. In a button, a post having a relatively wide head, ears projecting from the lateral edges of the said head to form bearing members, a back-plate having an opening therethrough to receive the post, the said ears of the latter adapted to bear against the adjacent face of the plate, and a cup-shaped outer shoe having an inwardly rolled peripheral edge inclosing the end portion of the post, including its ears, and the peripheral edge portions of the plate, whereby all the parts are rigidly clamped together.

4. A button or stud having main front and back heads, and a post connecting the heads, the portion of the post connecting the front head being relatively wide and approximately T-shaped, said front head comprising a disk-like plate having an opening to receive and support the corresponding portion of the post, the lateral ends of the post being superimposed upon the inner face of the plate, and a shoe in clamping engagement with the lateral ends of the post and with the exterior face of the plate for rigidly securing the parts together.

In testimony whereof I have affixed my signature in presence of two witnesses.

FRANK P. BARNEY.
